WINDOW SHADE FIXTURE

William H. Dollinger, Franklin, Ohio

Application May 2, 1934, Serial No. 723,583

2 Claims. (Cl. 156—10)

This invention relates to window shade fixtures and has for the primary object the provision of a combination device for supporting a shade with a protective shield therefor and also 5 is adaptable for the reception of rods employed for draperies, valances, curtains and the like.

With these and other objects in view this invention consists in certain novel features of construction, combination and arrangement of parts 10 to be hereinafter more fully described and claimed.

For a complete understanding of my invention, reference is to be had to the following description and accompanying drawings, in which

15 Figure 1 is a fragmentary front elevation, partly in section, illustrating a window frame with fixtures applied thereto and supporting a shade and curtains.

Figure 2 is an end elevation illustrating one of 20 the fixtures.

Figure 3 is a sectional view taken on the line 3—3 of Figure 1.

Figure 4 is a plan view illustrating a blank from which a combined supporting and holding 25 element is constructed.

Figure 5 is a perspective view illustrating an attaching bracket.

Figure 6 is an end view partly in section illustrating a modified form of my invention.

30 Figure 7 is a fragmentary front elevation partly in section illustrating my modified form of invention.

Figure 8 is a plan view illustrating a blank from which my modified form of invention is 35 constructed.

Figure 9 is an end elevation partly in section illustrating another modified form of my invention.

Figure 10 is a fragmentary vertical sectional 40 view illustrating the same.

Referring in detail to the drawings, the numeral 1 indicates attaching plates to be secured to a window frame 2 by screws, nails or like fasteners for the purpose of removably receiving a fixture 3 so that a window shade 4 and curtains 5 will be properly associated with the window of the frame 2. The fixture 3 includes a shield 6 and shade and curtain rod supporting elements 7. The shield 6 is arranged between the elements 7 and is of semi-cylindrical shape to protect the material of the shade while on its roller from dirt and like foreign matter but which will permit the shade material to readily wind onto and off of the roller. The shield 3 is provided with offsets 8 which fit within notches 9

of the elements 7 to prevent accidental displacement of the shield but which will permit the shield to be separated from the elements when necessary.

The combined shade and curtain rod supporting elements 7 are similarly constructed and each is made from a blank 10 including an elongated strip 11 and a disc-like portion 12. The blank may be composed of any material suitable for the purpose and one end of the strip 11 is enlarged, as shown at 13, and slotted in H formation, as shown at 14, while the opposite end of the strip is reduced in width. The strip 11 has the disc-like portion 12 integral therewith and is provided with a depression or offset to form 15 the notches 9. The strip 11 is bent in annular formation to form the shield engaging portion 15. The strip 11 after being bent into annular formation has the end 13 extended therefrom and bent upon itself to form a rest to engage 20 with the window frame 2 and the material between the H-shaped slot 14 is bent outwardly to provide spaced tongues 16 to be engaged by poles 17 for supporting curtains, draperies or the like. The other end of the strip 11 after the formation 25 of the annular portion is extended and bent upon itself to form a bracket engaging tongue 18 removably received within a pocket 19 formed in the plate or bracket 1.

From the foregoing description it will be seen 30 that the combined shade and rod supporting elements 7 can be easily applied or removed from the plates 1 and also may have the shield 3 applied and removed therefrom as well as the poles 17.

The portion 12 of the blank 10 and after bending of the strip 11 of said blank into annular formation is bent to close one side of the annular portion or the portion engaged by the shield and is either provided with a slot or opening to receive the pintles of the shade roller. The disc-like portion 12 instead of being provided with a slot or opening may be depressed or offset to receive the pintles of the shade roller.

Tongues may be formed integrally with the 45 strips 11 to be bent into engagement with the disc-like portions 12 for retaining the latter within the annular portion or shield engaging portion of the fixture elements 7 and these tongues are indicated by the character 19 in Figure 9. Said Figures 9 and 10 also show that the end portions of the strip after the bending of the latter into an annular formation may be offset laterally from said annular portion and bent in opposite directions to form attaching portions 20 apertured to receive 50 55

nails or like fasteners 21 for securing the attaching portions directly to the window frame.

Instead of employing a blank, as shown in Figure 8, a blank 20' may be used in the construction 5 of the combined shade and curtain rod supporting element and it is to be noted that this blank has the disc omitted therefrom, otherwise it is constructed similarly to the blank shown in Figure 8. When the blank 20' is employed, a disc, as 10 shown in Figure 1, is used in conjunction therewith. This type of disc is flanged to fit within the portion 15.

Having described the invention, I claim:

1. An annular member for removably securing 15 a semitubular shaped shield, a disc-like element integral with said annular member and provid-

ing a support for an end of a shade roller located within the shield, said annular member carrying a pair of offset portions and one of said offset portions providing a bracket engaging ear and the other offset portion forming a rest to engage with a window frame and having struck therefrom tongues to form attaching mediums for curtain rods.

2. A window shade fixture including an annular member for supporting an end of a shield, a disc-like element integral with the annular member and forming a support for a shade roller, and tongues on said annular member and bent to engage the disc-like element, the annular member being securable to a window frame.

WILLIAM H. DOLLINGER.
